UNITED STATES PATENT OFFICE.

ERNEST H. SCHMIDT, OF CLEVELAND, OHIO, ASSIGNEE TO THE NATIONAL MALLEABLE CASTINGS COMPANY, OF CLEVELAND, OHIO, A CORPORATION OF OHIO.

RADIAL-DRAFT GEAR.

1,209,189.

Specification of Letters Patent. Patented Dec. 19, 1916.

Application filed May 18, 1915. Serial No. 28,815.

To all whom it may concern:

Be it known that I, ERNEST H. SCHMIDT, a citizen of the United States, and a resident of Cleveland, Cuyahoga county, Ohio, have 5 invented new and useful Improvements in Radial-Draft Gears, of which the following is a specification, reference being had to the accompanying drawings, in which—

Figure 1 is a vertical section of a radial 10 draft gear embodying my invention; Fig. 2 is a horizontal section thereof, on line II—II of Fig. 1; Fig. 3 is a detail plan of the forward casing, Fig. 4 is a side elevation thereof, Fig. 5 is a rear end elevation 15 thereof; Fig. 6 is a detail plan of the rear casing, Fig. 7 is a side elevation thereof, Fig. 8 is a rear end elevation thereof; Fig. 9 is a section on the line IX—IX of Fig. 1; Fig. 10 is a section on line X—X of Fig. 1; 20 and Fig. 11 is a section on line XI—XI of Fig. 1.

My invention relates to radial draft gear and consists in a draft member provided with a pair of telescoping casings, and a 25 shock absorbing mechanism, which has a buffering engagement with one casing and a pulling engagement with the other casing.

My invention also consists in the construction and coöperation of the parts which 30 I shall hereinafter describe and claim.

Referring to the drawings, A indicates the coupler, which is attached to a forward casing B, C indicates the rear casing and D the shock absorbing container.

The forward casing B has at its forward 35 end a forwardly extending flaring pocket 2, adapted to receive couplers of differently-dimensioned shanks within the pocket. The shank pocket 2 is provided upon its top and 40 bottom walls with shoulders 3, adapted to support the shank of a coupler and hold it level, as is shown in Fig. 1. The coupler A may be secured in the pocket 2 in any suitable manner, such as by the keys 4, bolt 5 45 and keepers 6, as shown in Fig. 1.

At the rear of the pocket 2 the casing B has an annular portion 7, adapted to receive the forward end of the shock absorbing container D. Extending to the rear of 50 the annular portion 7 is a pair of horizontally-arranged arms 8 having slots 9 in their rear ends for reception of a key 10, by which the arms are secured to the follower 11, which normally bears against the curved forward face of the pivot casting 12. The

slots 9 are elongated to permit the casing B to move rearwardly relatively to the key 10 and follower 11 during buffering. The shock absorbing mechanism, which I have shown in the form of a cylindrical container 60 D adapted to contain frictional mechanism, seats at its forward end in the annular portion 7 of the casing B, and has at its rear end outwardly-extending shoulders 13, with which the forward annular portion 14 of 65 the rear casing C coöperates during draft.

The casing C has two rearwardly-extending arms 15, arranged one above the other, apertured for pivotal attachment to the pivot casting 12, which is secured to the car 70 structure. The arms 15 have flanges 16, which extend about the arms 8 of the casing B to prevent spreading of the latter, as is shown in Figs. 10 and 11. To maintain the key 10 in position, a bolt 17 is provided, 75 which extends through the arms 15 of the rear casing C and through the key 10, and thereby holds the key against lateral movement.

The operation of the device is as follows: 80 In draft the pull is transmitted by the coupler A through the pocket 2 of the forward casing B to the arms 8 of that casing, and thence through the key 10 to the follower 11, and the follower 11 is thereby 85 pulled forwardly against the resistance of the shock absorbing mechanism D. The container D is prevented from moving forward by the engagement of its shoulders 13 with the rear edge of the ring 14 at the forward 90 end of the rear casing C, which is attached to the pivot casting 12. It will, therefore, be seen that under draft the pull from the coupler is transmitted to the car through the pocket 2 by means of the keys 4, to the 95 arms 8, to key 10, to follower 11, to shock absorbing mechanism D, to ring 14 of rear casing C, to arms 15, and thereby to the pivot casting and the car. In buffering the rear wall of the coupler pocket 2 abuts 100 against the forward or closed end of the friction case D and carries it rearwardly. The rear casing C remains stationary and the arms of the forward casing B slide in the slots formed by the anti-spread flanges 16 of 105 the arms 15. The follower 11 and key 10 remain stationary, the elongated slots 9 in the arms 8 allowing said arms to travel rearwardly without interference with the key 10.

The frictional parts abutting against the 110

follower 11 are held stationary, while the container D, as above described, moves rearwardly over these parts, actuating them frictionally, thereby taking up the shock.

5 As is shown in Fig. 11, the container D is preferably constructed with flattened sides 18, so that, in assembling, it may be slid forwardly between the arms 15 of the casing C with the flattened sides arranged in line with 10 these arms, so as to permit the shoulders 13 to pass the inwardly-extending strengthening flanges 19 on the case C about the bolt 17. When the container D has been slid forwardly as just described, it is then rotated 15 90 degrees to bring its shoulders 13 into engagement with the rear edges of the ring 14.

The container D is reinforced against bursting stresses by arranging the ring 14 on the rear casing C to overlie the shock-absorbing container D near the point at 20 which it receives the greatest stress from the contained frictional parts. The drag of the friction shoes upon the casing is, therefore, transmitted in draft directly through the 25 case to the ring 14 of the rear casing, thus relieving the forward part of the case D from the greater part of the tensional stress.

The terms and expressions which I have employed are used as terms of description 30 and not of limitation, and I have no intention, in the use of such terms and expressions, of excluding any mechanical equivalent for the features shown and described, but recognize that various structural modifi-

cations are possible within the scope of the invention claimed.

What I claim is:

1. In a radial draft gear, a forward member connected to the coupler, a rear member pivotally connected to the car, a container 40 for a shock absorbing mechanism co-operating with both members, the said container having outwardly extending lugs engaging an inwardly extending portion of the rear member during draft, and having at its forward end a bearing with which the forward member co-operates during buffing. 45

2. In a radial draft gear a forward member connected to the coupler, a rear member having rearwardly extending arms pivotally connected to the car, shock absorbing mechanism, a follower, the said follower having a key connection with one of said members and being adapted under draft to transmit the pulling stresses to the shock absorbing 50 mechanism, and under buffing to transmit the buffing stresses from the shock absorbing mechanism to the car. 55

3. In a radial draft gear, a forward member connected to the coupler and a rear member connected to the car, and a shock absorbing casing contained in the rear member and having a pulling engagement therewith, the casing being adapted to be inserted into the rear member from the rear and after insertion to be rotated 90 degrees to be brought 60 into pulling engagement therewith. 65

ERNEST H. SCHMIDT.
